(57) **CLAIM**

The ornamental design for a hinge pin, as shown and described.

DESCRIPTION

FIG. 1 is a perspective view of a hinge pin assembly in a fully assembled condition, showing our new design;

FIG. 2 is a front view of the fully assembled hinge pin assembly of FIG. 1, the rear, top, and bottom views being the same;

FIG. 3 is a left side view of the fully assembled hinge pin assembly of FIG. 1;

FIG. 4 is a right side view of the fully assembled hinge pin assembly of FIG. 1;

FIG. 5 is a front perspective exploded view of the hinge pin assembly of FIG. 1 in an un-assembled condition;

FIG. 6 is an enlarged front view of the pin-portion of the hinge pin assembly of FIG. 5, shown separately for clarity;

FIG. 7 is a left side view of the pin of FIG. 6;

FIG. 8 is a right side view of the pin of FIG. 6;

FIG. 9 is an enlarged front view of the bushing portion of the hinge pin assembly of FIG. 5, shown separately for clarity;

FIG. 10 is a left side view of the bushing of FIG. 9; and,

FIG. 11 is a right side view of the bushing of FIG. 9.

FIG. 1**FIG. 2****FIG. 3****FIG. 4****FIG. 5****FIG. 6****FIG. 7****FIG. 8****FIG. 9****FIG. 10****FIG. 11**
